Benjamin D. Reacher
Letters Patent

The Schedule annexed to in these Letters Patent are making part of
the same containing a description in the words of the said Benjamin
D. Reacher himself of his improvement in a combination of machine
or for thrashing grain, shelling corn, cutting straw and grinding groats.

This combination of machinery consists of a frame made of timber of the
size of 4 inches square, to feet in length or more 8 feet wide, &
the same in height. 2nd A cylinder is made of wood about
sixteen inches in diameter, thirty inches in length, upon which
are six, eight or ten projections, of about three boards of an inch
each with iron running transversely from the centre in such
manner that the centre comes first in contact, and sloping so
as to leave the instant the second beater commences its action.
3rd Over this is a concaved covering, one sixth its circum-
ference, made of thin plates of iron, placed between pieces of
wood, at a distance of one fourth of an inch, projecting three
sixteenths of an inch. This rests on the upper side of the frame &
is kept down by spiral or other springs. 4th In front is a
fluted roller six inches in diameter to confine the straw and make
it feed. 5th Under this is a roller two and a half inches
in diameter suspended on springs, in such a manner as to give
downward, one and a half inch. Around this they feeding upon
rollers. 6th a wheel three feet three inches in diameter and
three inches in thickness is placed on one side of the machine
at a distance of three feet from the cylinder on a shaft pas-
sing through the machine on which is a cylinder five inches in
diameter round which the apron passes and by means of which
it is driven. 7th Around the wheel passes a band
which runs under a pulley on the fluted end of the roller, three
fourths of the way round a roller two and a half inches

in diameter on the cylinder shaft. 9th This wheel is put in motion by cranks or gears or a band wheel, by hand, horse, water, or other power. 9th This wheel is armed with teeth on the side toward the machine from the edge inward sixteen inches which with a half circle toothed in like manner suspended in springs against the side of the frame so as to conform to the edge of the car which forms a corn shelter.

10th It has a section of one tenth its circumference and of its thickness which may be increased at pleasure, one side being armed with teeth, and a knife on the other, which with a small bar placed across the machine forms a straw cutter.

11th About eleven inches of the center of the wheel is left upon which is a plate of cast iron turned in such a manner as that with a corresponding plate fastened to the frame with a suitable hopper forms a mill for grinding grain - What I claim as my invention and improvement is the particular form of the beater and manner of making the concave, turning the feeding roller by the main band, the spout by the main shaft, and the mode of combining the several pieces of machinery.
